UNITED STATES PATENT OFFICE.

EDWARD POOLE, OF HALIFAX, ENGLAND, ASSIGNOR TO JOSEPH WILD
& CO., OF NEW YORK, N. Y.

DESIGN FOR A CARPET-PATTERN.

Specification forming part of Design No. 5,908, dated June 4, 1872.

To all whom it may concern:

Specification describing a new and original Design for a Carpet, invented by EDWARD POOLE, of Halifax, in the county of York, England.

The accompanying photograph fully illustrates my invention.

This invention relates to a new design for carpets and other fabrics. Said design consists of two main figures, of which one has an outline nearly square, while that of the other is composed of eight ogee curves. The

latter contains an irregular central field with a bird therein, as shown, while the center of the square figure contains a bow, quiver, and musical instrument. Floral wreaths, branches, and garlands are dispersed throughout both figures, as shown.

I claim as my invention—

The design for a carpet, as shown.

EDWARD POOLE.
